[57] CLAIM

The ornamental design for a fence runner, as shown and described.

DESCRIPTION

FIG. 1 is a perspective view of a fence runner showing my new design;

FIG. 2 is a sectional view taken along line 2—2 of FIG. 1 and drawn to a larger scale;

FIG. 3 is a top plan view of a portion of the fence runner shown in FIG. 1;

FIG. 4 is a bottom plan view of a portion of the fence runner shown in FIG. 1; and,

FIG. 5 is a side elevational view of a portion of the fence runner shown in FIG. 1, the opposite side being a mirror image thereof.

Fig. 2

Fig. 3

Fig. 4
